UNITED STATES PATENT OFFICE.

HENRY G. SWEENEY, OF CHICAGO, ILLINOIS.

VENDING-MACHINE.

SPECIFICATION forming part of Letters Patent No. 611,226, dated September 20, 1898.

Application filed February 8, 1897. Serial No. 622,408. (No model.)

To all whom it may concern:

Be it known that I, HENRY G. SWEENEY, a citizen of the United States, residing in Chicago, in the county of Cook and State of Illinois, have invented a new and useful Improvement in Vending-Machines, of which the following is a specification.

This invention relates to certain improvements in machines for vending or dispensing liquids. Some of its features relate to the construction of the coin-controlling mechanism.

The object of the invention is the production of a machine which shall be simple and economical of construction, durable, have small liability to get out of order, and which cannot be successfully tampered with or robbed of its liquid.

The nature of my improvements is illustrated in the accompanying drawings and also fully set forth in the description given below.

In the drawings, Figure 1 is a vertical section of that portion of a liquid-vending machine to which my improvement relates, showing the coin mechanism in its normal position. Fig. 2 is a similar section to Fig. 1, partly broken away and showing the coin mechanism at the conclusion of a delivery. Fig. 3 is a horizontal section showing the coin mechanism in its normal position. Fig. 4 is a longitudinal section of the valve used in the form of apparatus shown at Fig. 2. Figs. 5 and 6 are transverse sections of the same valve, showing its different positions. Figs. 7 and 8 are cross-sections of valves used in the apparatus of Fig. 1.

In said drawings, A represents the case or box of the machine, only one side thereof being given. B represents the coin-chute, and C is the receiver into which the coin falls from the chute. The receiver is mounted upon the end of an arm C', fast upon the pivot C², supported by a bracket C³, rising from a horizontal frame C⁴, attached to the case A. A forked dog C⁵, also mounted on said pivot and projecting therefrom in the opposite direction from that of arm C', is adapted, when a coin is dropped into the receiver and depresses it and arm C', to lift the locking-detent D, loosely supported upon pivot C², out from engagement with the ratchet-wheel D', revolving upon journal D², supported in

frame C⁴. In the performance of this duty one arm of the dog encounters an overhanging arm or projection D³, attached to detent 55 D, and by such engagement operates the detent. The wheel is a double one, having on one side of its periphery a series of teeth D⁴ for engagement by said detent in stopping the wheel at the conclusion of a delivery and 60 on the other side a series of teeth D⁵ for engagement by the pallet D⁶ in moving said wheel. Said pallet is freely pivoted upon one end of an elbow - lever D⁷, swinging upon pivot D⁸, supported in frame C⁴, and the other 65 end of said lever projects through the case A, as shown, to permit it to be operated. The lever is depressed by the purchaser to the position shown at Fig. 2, and thereby causes a partial rotation of wheel D', and at the conclusion of the stroke so imparted the lever is 70 lifted to its normal position, given in Fig. 1, by a spring D⁹, one end of which lifts upon the projecting arm of the lever.

The pallet D⁶ carries a laterally-projecting 75 pin D¹⁰, which when the pallet is drawn forward by the operating-lever enters the fork of the dog C⁵ and by its engagement therewith causes the swinging of the coin-receiver from the position of Fig. 1 to that of Fig. 2, 80 so that the coin will be discharged from the receiver. This pin also forces the receiver back to its normal position by its engagement with the dog during the retraction of the pallet. The ratchet-wheel can be rotated 85 in one direction only—viz., the forward direction—as a gravity-stop D¹¹, pivoted upon frame C⁴, engages the teeth D⁵ and absolutely prevents any backward movement whatever.

Power is carried from the pallet-wheel to the valve or valves controlling the liquid by the following devices: A swinging lever E, pivoted at E' to frame C⁴, carries upon its upper end a cam E², made fast by rivet E³, and 95 encountering two series of alternately-acting pins E⁴ and E⁵, carried by and projecting from the side of ratchet-wheel D'. As shown at Fig. 1, one of the series E⁵ of the pins is in contact with the under surface of the cam 100 and in such relation thereto that any forward movement of the wheel will cause the cam to exert a pressure against lever E, which will result in its moving to the position given in

broken lines in said figure and in full lines at Fig. 2. The movement of the wheel brings one of the pins E^4 close against the cam, as seen at Fig. 2, so that at the next impulse given the wheel said pin will carry the cam and lever E back to their former positions, (shown at Fig. 1,) the cam and lever being thus left at the conclusion of each operation in proper positions and ready for the next operation. The movements thus given to lever E are carried to the crank-arm E^6 on the stem-valve by a connecting-rod E^7 .

In Fig. 1 I have illustrated a form of apparatus to be used in dispensing liquids which are under pressure when fed to the measuring-receptacles of the machine. I prefer to use duplicate receptacles, such as F and F' , and to employ therewith a single valve adapted to permit the filling of one of the receptacles while the other is delivering its charge to a purchaser. Suitable forms of these valves are shown at G and G^a . Each is provided with two cross-passages G' , similar in form and located at opposite sides of the valve-axis. The valve is located at the junction of the following pipes—to wit, pipes F^2 and F^3 , connecting the valve with the measuring-receptacles, the feed or supply pipes F^4 and F^5 , one for each receptacle, and the delivery-pipe F^6 . Of these pipes F^2 and F^4 are close together, so as to be controlled by one of the cross-passages of the valve, and the pipes F^3 and F^5 are similarly arranged, so as to be controlled by the other cross-passage. When these pipes are in the same vertical plane, the construction of valve shown at Figs. 5 and 6 is used; but when located in different planes a valve like that at Figs. 7 and 8 is used, the fluid-passages therein being located in planes corresponding to those of the pipes, and a Y , like that shown at M , being also used to connect both ends of the valve with the discharge-pipe. The valve, whichever form is used, has two positions, as will be understood, and in each of them it acts to deliver the charge contained in one of the receptacles and simultaneously permit the filling of the other receptacle, and it is oscillated from one to the other of these positions at each operation of the actuating mechanism by a purchaser. Subsequent operations will be mere repetitions of those described, and each of them leaves the valve in readiness for the next operation without any intervening positioning movement of any description.

In the apparatus shown at Fig. 1 a vent-valve H is placed at the top of each of the receptacles, and its stem is provided with a crank H' , which is connected by a rod H^2 with a crank H^3 upon the stem of the main valve. These vent-valves are adapted to admit air at the top of the receptacles and above the liquid at the time the latter is discharged, and my object in employing them is to insure the prompt discharge of the entire body of the liquid and prevent as far as possible any

dripping or after drainage which will tend to keep the machine untidy. I find that the use of this vent causes the quick delivery of the entire body of the liquid, so that but little or no after dripping occurs. 70

In Figs. 2 and 4 an apparatus is shown adapted to dispense mixed drinks, the measuring-receptacles for the main liquid being similar to that used in the other apparatus, except that they are provided with permanently-open vents H^a instead of the valved vents of Fig. 1. The liquid-supply is kept in a tank J , connected to the valve by supply-pipes in the usual manner. The flavoring extract is also measured in corresponding companion cups or receptacles, one of which is shown at K , and such receptacles are connected by pipes L to the valve G^a . The pipes from the receptacles F F' in this apparatus join the valve opposite one set of passages G' at one end of the valve, and the pipes from receptacles K join it opposite another set of such passages at the other end 90 of the valve, as will be understood from Fig. 4, the Y (indicated by M) connecting both ends of the valve and causing the intermingling of the main fluid and the flavoring extract as soon as the valve is operated to effect the discharge. 95

I claim—

1. The combination in a liquid-dispensing machine, of companion measuring-receptacles for the main liquid, both connected to the supply and discharge, companion measuring-receptacles for the flavoring-syrup also connected to the supply and discharge, an oscillating valve controlling all said receptacles and having two positions in each of which it permits the discharge from one of each pair of said receptacles and the filling of the others, and coin-controlled mechanism for operating said valve alternately in opposite directions, substantially as specified. 100 105 110

2. The combination in a machine for dispensing mixed beverages, of two companion measuring-receptacles for the main liquid, two companion measuring-receptacles for the flavoring-syrups, a valve provided with two cross-passages connecting with said main receptacles and with two other cross-passages connecting with the syrup-receptacles, and coin-controlled mechanism for operating said valve, substantially as specified. 115 120

3. The combination in a machine for dispensing mixed beverages, of two companion measuring-receptacles for the main liquid both having connections with a source of supply and with the discharge two companion measuring-receptacles for the flavoring-syrup, also connected to a source of supply and to the discharge, and a single valve controlling all said connections to the sources of supply and to the discharge, substantially as specified. 125 130

4. The combination in a machine for dispensing mixed beverages, of two companion measuring-receptacles for the main liquid both having connections with a source of sup-

- ply and with the discharge two companion measuring-receptacles for the flavoring-syrup, also connected to a source of supply and to the discharge, and a single valve provided 5 with two cross fluid-passages controlling the admission and discharge from the main liquid-receptacles and two other cross fluid-passages controlling the admission and discharge from the syrup-receptacles, substantially as 10 specified.
5. The combination in a machine for dispensing mixed beverages, of two companion measuring-receptacles for the main liquid, both having connections with a source of 15 supply and with the discharge two companion measuring-receptacles for the flavoring-syrup, also connected to a source of supply and to the discharge, and a single valve controlling the admission and discharge from all 20 the receptacles, and allowing one of each pair of them to fill while the others are emptying, substantially as specified.
6. In a liquid-vending machine, the combination with an oscillating valve controlling 25 the delivery, of a lever projecting outside of the machine so it may be operated by the purchaser, a wheel receiving step-by-step movements in one direction from said lever and mechanical connections acting to carry power 30 from the wheel to the valve and to actuate it alternately in opposite directions substantially as specified.
7. In a liquid-vending machine, the combination with an oscillating valve controlling 35 the delivery, of a lever projecting outside of the machine so it may be operated by the purchaser, a wheel receiving step-by-step movements in one direction from said lever, coin mechanism controlling said wheel, and me-
- chanical connections acting to carry power 40 from the wheel to the valve and to actuate it alternately in opposite directions, substantially as specified.
8. The combination of a swinging coin-receiver, a forked dog fast upon the pivot of 45 the receiver, a pallet D⁶ having a pin D¹⁰ entering between the fork-arms of the dog, and a lever to be operated by the purchaser and actuating the pallet, substantially as specified. 50
9. The combination with the lever E, of the wheel rotating step by step in one direction and having two series of pins E⁴ and E⁵ projecting from its side, and the cam E² fast to one end of said lever and engaging said pins, 55 substantially as specified.
10. In coin-controlling mechanism, a pivotally-supported coin-receiver adapted to be swung over its axis in discharging the coin, in combination with a forked dog swinging 60 with the receiver, a pin D¹⁰ entering between the arms of the dog, a movable support for said pin, and a lever operated by the purchaser and actuating said pin-support, substantially as specified. 65
11. In coin-controlling mechanism, a pivotally-supported coin-receiver adapted to be swung over its axis in discharging the coin, in combination with a forked dog secured upon the axis of the receiver, a pin D¹⁰ entering between the arms of the dog, a movable support for said pin, and means for actuating said support so as to cause the swinging of the receiver, substantially as specified. 70
